Primary Examiner — Sandra Snapp*Assistant Examiner* — Ieisha N Price(57) **CLAIM**

The ornamental design for a screw, as shown and described.

DESCRIPTION

FIG. 1 is a front, left-side perspective view of the screw according to the invention.

FIG. 2 is a rear view of the screw.

FIG. 3 is a left view of the screw

FIG. 4 is a front view of the screw.

FIG. 5 is a right-side view of the screw.

FIG. 6 is a top plan view of the screw.

FIG. 7 is a bottom plan view of the screw; and,

FIG. 8 is a top, right-side perspective view of the screw. The broken lines in the drawings illustrate portions of the screw and form no part of the claimed design.
